UNITED STATES PATENT OFFICE.

FRANCIS BRUNSON, OF DECKER, INDIANA.

SAW-HANDLE.

SPECIFICATION forming part of Letters Patent No. 278,088, dated May 22, 1883.

Application filed February 14, 1883. (No model.)

To all whom it may concern:

Be it known that I, FRANCIS BRUNSON, a citizen of the United States of America, residing at Decker township, in the county of Knox and State of Indiana, have invented certain new and useful Improvements in Saw-Handles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a saw-handle designed especially for use on crosscut-saws, its object being to enable the strength of the sawyer to be exerted directly in line with the saw-blade, and to provide a strong and durable handle which may be readily attached to the saw or removed therefrom.

The invention consists in the novel construction and combination of parts, which will be hereinafter particularly described, and pointed out in the claims.

In the accompanying drawings, Figure 1 is a side elevation of a portion of a saw having my improved handle attached thereto. Fig. 2 is a longitudinal section on the line *xx*, Fig. 3; and Fig. 3 is a detached perspective view of the clamp.

The letter A indicates the metallic hand-frame, composed of the head-piece *b*, arms *c*, the ends of which pass through the hand-piece D, and are firmly secured therein by any suitable means. The head-piece *b* is slotted longitudinally to receive the end of the saw-blade S, as indicated by dotted lines, Fig. 1. At about the middle of the head-piece is formed a through-socket, as shown at *e*, to receive a slotted clamping-pin, F, which is provided with a screw-threaded shank, *f*, to receive a thumb-nut, *g*. The socket *e* of the head-piece flares somewhat at its outer end, as shown at *e'*, and the pin F has a bevel-shoulder, *h*, which enters the flaring end of the socket. When the end of the saw is inserted in the slit *f'* of the pin F, and also in the slit in the head-piece *b*,

the thumb-nut *g* is to be screwed up against the back of the head-piece, thus drawing the beveled shoulder *h* of the pin F into the mouth of the socket, and causing the parts of the pin F on opposite sides of the slit *f'* to be forced toward each other and firmly clamp the saw, so that its end edge will be held snugly against the rear wall of the slit in the head-piece, so that there can be no vibration of the handle. Through the projecting portion of the pin F is formed an aperture to receive a small locking-pin, *i*, which passes through an aperture in the saw-blade for the purpose of locking the same to the pin F, from one side of which springs a finger, *k*, bent to terminate opposite the head of the pin *i*, and at such distance from the pin F that the said pin *i* can only be withdrawn a sufficient distance to leave clear the slit in the pin F without escaping from said pin. By this means I effectually prevent the locking-pin from ever becoming lost or misplaced.

The manner of using my improved saw-handle will be perfectly clear from an inspection of the drawings.

Having now fully described my invention, I claim—

1. The combination, with the slotted clamping-pin F and the locking-pin *i*, arranged in an aperture in said clamping-pin, of the finger *k*, having its end opposite the head of said locking-pin, substantially as and for the purpose set forth.

2. The herein-described saw-handle, composed of the frame A, having the slotted and socketed head-piece *b* and arms *c*, the hand-piece D, secured to said arms, and the slotted clamping-pin F, provided with the guard-finger *k*, bevel-shoulder *h*, screw-shank *f*, thumb-nut *g*, and locking-pin *i*, substantially as described.

In testimony whereof I affix my signature in presence of two witnesses.

FRANCIS BRUNSON.
